PROSPER ERHARD AND AMELIE ERHARD, OF NEW YORK, N. Y.

Letters Patent No. 91,614, dated June 22, 1869.

IMPROVED FABRIC FOR THE MANUFACTURE OF HATS, BONNETS, AND VARIOUS ARTICLES FOR USE AND ORNAMENT.

The Schedule referred to in these Letters Patent and making part of the same.

To all whom it may concern:

Be it known that we, PROSPER ERHARD and AMELIE ERHARD, of the city, county, and State of New York, have invented a certain new and useful Fabric or Article of Manufacture from the Bark of the Bass or Linden-Tree; and we do hereby declare the following to be a full and correct description of the same.

We take the ordinary thin slips, or shavings of the bass-wood tree, known in commerce as "Cuba bast," and divide it into ribbons of any desired width.

These ribbons we interweave, plait, braid, or otherwise combine, at right angles, diagonally, or at any desired angle with each other, or with other materials, so as to form a fabric of any desired width, size, or pattern.

When for head-coverings, we combine the material without sewing. When for ornamental purposes, such as dress-trimmings, we give the required form by gluing, pasting, sewing, and stamping, or by any one or more of these processes. Hats and bonnets are made by stamping.

We use the substance either in its natural color, or stained by dyes, paint, varnish, bronze, powder, or other materials, to any hue or shade we may wish.

Dyeing is performed before the fabric is made up.

Paint, varnish, bronze, powder, and the like, are imposed after the form is given.

The surface of the material may either be plain, or ornamented with figures in relief made by stamping. Under all varieties of form and hue, it presents an ornamental and beautiful surface.

What we claim as our invention, and desire to secure by Letters Patent, is—

The use of the bast of the bass-wood, or linden, or other vegetable "basts," in the production of a fabric applied to the manufacture of hats, bonnets, dress-trimmings, and other useful and ornamental articles, substantially in the manner described.

The above specification of our said invention signed and witnessed, at New York, this 16th day of December, A. D. 1868.

PROSPER ERHARD.
AMELIE ERHARD.

Witness to both signatures:

W. H. MELICK.

Witness to AMELIE ERHARD:

J. H. STEPHENSON.
